UNITED STATES PATENT OFFICE.

WILLIAM S. MYERS AND AMZY L. SMITH, OF ASHLAND, KENTUCKY, ASSIGNEES OF
ONE-THIRD TO C. R. WILSON, OF CHICAGO, ILLINOIS.

PORTABLE BORING AND GRINDING DEVICE FOR AUTOMOBILE-CYLINDERS.

1,339,409.

Specification of Letters Patent. Patented May 11, 1920.

Application filed June 18, 1919. Serial No. 305,023.

To all whom it may concern:

Be it known that we, WILLIAM S. MYERS and AMZY L. SMITH, both citizens of the United States, and residents of Ashland, in the county of Boyd, State of Kentucky, have invented certain new and useful Improvements in Portable Boring and Grinding Devices for Automobile-Cylinders, of which the following is a specification.

10 Our invention relates to a device for machining the cylinders of internal combustion engines and particularly to a novel device adapted to be directly mounted upon an engine casting for the purpose of boring and 15 grinding the cylinders thereof without removing the engine from the car.

It frequently becomes necessary to refinish the cylinders of automobile engines due to scoring, pitting and wear of the cylinders 20 and this has heretofore been effected only by removing the engine from the automobile and placing it successively in boring or grinding machines. Not only does this involve considerable expense in the matter of 25 labor in removing and returning the engine but entails additional expense because of the labor of skilled mechanics in adjusting the engine in the boring and grinding machines.

Our improvement contemplates the construction of a simple portable machine having a double function and adapted to be placed in proper position on an automobile engine after the head thereof has been removed and which will sequentially or simultaneously 30 grind and bore the cylinders. By the use of this machine the relatively great expense heretofore entailed in these operations is materially reduced, the desired results may be secured by any competent garage mechanic, and the owner is not deprived of his automobile for great lengths of time.

The desired result is secured by providing a simple casting, comprising a base and standard, the base being adapted to rest upon and to be temporarily secured to a cylinder casting, the standard containing bearings for a relatively massive shaft to the lower end of which a head is secured. 45 Adjustably mounted in this head is a cutting tool and an emery wheel, both of which are adapted for bodily rotation with the shaft, the emery wheel having a planetary movement, the rotation being effected by a shaft arranged internally of the large shaft.

The construction is adapted for other garage uses, as the head which carries the tools referred to may be removed and replaced by a drill chuck if required.

The invention will be more readily understood by reference to the accompanying drawings, wherein,

Figure 1 is a side elevation of our improved device showing it in operative relation to a cylinder casting;

Fig. 2 is a plan view thereof;

Fig. 3 is a bottom plan view of the cutter head; and,

Fig. 4 is a side elevation of the construction shown in Fig. 3.

Fig. 5 is a detail side elevation of the feeding mechanism;

Fig. 6 is a back view thereof; and,

Fig. 7 is a plan view.

In the drawings it will be seen that we provide a casting which comprises a base 10 and a standard 11, the base resting upon and being adapted to be temporarily secured to a cylinder casting, such as shown in Fig. 1. The standard is provided with brackets 12, 13, 14, which contain bearings for vertically movable and rotatable shafts 15, 16. The shaft 15 is mounted within a large sleeve 17 which is vertically movable in the bearings 12, 13, while the shaft 16 is mounted centrally within the shaft 15. A head 18 is secured to the lower end of the shaft 15, as best shown in Figs. 3 and 4, being provided with radial dove-tailed grooves 19, 20. Within the space formed by the radial 85 groove 19 is mounted a properly shaped block 21 having an arm or bracket 22 secured thereto carrying at its lower end a bearing 23 for a short shaft 24. An emery wheel 25 is mounted on one end of the shaft 90 and a pinion 26 on the opposite end. As stated the shaft 16 extends downwardly through the shaft 15 and terminates at its lower end in a gear 27 adapted to mesh with an idler gear 28 carried by an arm 29, 100 which is mounted for oscillation on the center of the shaft 16. The arm is adapted to engage an arcuate rib 30 on the lower face of the head 18 and be held in adjusted position by the set screw 31. The idler 28 engages the gear 26 and causes rotation of the emery wheel.

Provision is made for radial adjustment of the block 21, such as the screw 32, the block being held firmly in position by means 110

of the screw 33. The in and out adjustment makes necessary the idler 28 and the oscillating arm on which the idler is mounted. As the grinding wheel is moved radially it 5 will be seen to be necessary to swing the arm 29 to bring the idler into mesh with the grinding wheel gear 26.

The groove 20 on the diametrically opposite side of the head accommodates what is 10 in effect a tool post 34 within the lower end of which a cutting tool 35 is secured by means of the set screw 36. This member has capacity for in and out adjustment by 15 similar mechanism as that described in connection with the grinder.

The parts are rotated by means of an electric motor 37 having two belt wheels 38, 39. A belt 40 extends from the pulley 38 to a large idler pulley 41 which carries a 20 small idler pulley 42, a belt 43 connecting the small pulley to a large pulley 44, which is rigid with a shaft 45 carried in suitable bearing at the upper end of the machine. A bevel pinion 46 is secured to the shaft 45 25 and engages a large bevel gear 47 splined to the shaft 15 whereby this shaft to the lower end of which the head 18 is secured, is caused to rotate. The belt 48 extends from the large pulley wheel 39 over suitable 30 idler pulleys 49 to a small pulley 50 mounted in suitable bearings and splined to the shaft 16 which causes the rotation of the grinding wheel.

Also splined to the shaft 15 is a sprocket 35 wheel 51 which is connected by a chain 52 to a sprocket wheel 53, as best shown in Fig. 1. The wheel 53 is rigid with a shaft 54 having a worm at its lower end, the worm engaging a worm wheel 55 on a shaft 40 56. This shaft serves to effect automatic feed of the tools in a vertical direction. Hand feed may also be effected by the hand wheel 57, the feeding devices engaging a 45 rack 58 which is connected to the sleeve 17 and causes vertical reciprocation thereof in the usual manner.

As shown in Fig. 5 the shaft 56 is provided with a small toothed wheel 59 at its end. Mounted on a shaft 60 in proximity to the 50 wheel 59 is a plate 61, adapted to be oscillated by means of the projection or handle-grip 62. Mounted on this plate is an idler gear 63, permanently in mesh with a gear 64 secured to the end of the shaft 60. Also 55 secured to the plate is a smaller idler gear 65, the gears 63, 65 being constantly in mesh with each other and being adapted to be successively moved into mesh with the gear 59 by the oscillation of the plate. The gear 60 65 is not in mesh with the gear 64. The shaft 60 carries a worm 66 which engages a worm gear 67 secured to a shaft 68. This shaft carries a gear 69 which engages with the rack 58 and serves to effect the up and 65 down movement of the rotatable shafts 15,

16, which carry the cutting and grinding heads. By oscillating the plate 61 the gears 63, 65 may be alternately brought into operative relation and upward and downward movement secured.

When it is desirable to adjust the feed by hand, the automatic feeding mechanism is disengaged in the following manner: It 70 will be noted that the gears and shaft 56 are mounted in bearings carried by a frame 75 which is indicated by the numeral 70 in Fig. 6, this being slidably mounted on the bracket 71, which is secured to the standard of the machine. The frame 70 is held in desired position by means of the cam 72, 80 operated by the arm or handle 73. As the arm 73 is oscillated the frame which carries the gears, including the worm gear 63, may be raised and lowered as desired, thus moving the worm gear 66 out of and into 85 engagement with the worm gear 67. When raised out of engagement, the vertical movement of the cutting and grinding heads may be effected manually by means of the hand wheel 57.

If a drill chuck or similar device is to be employed the head 18 is detached from the shaft 15 and the desired tool applied in its place.

In the construction shown in Fig. 1 the 95 device is associated with an engine casting and a combined cutting and grinding action has been effected. It will be noted that the emery wheel has a planetary action and that it may be operated simultaneously with the 100 cutting tool. This effects a saving in time as it requires but a single adjustment for each cylinder.

Obviously the motive power might be changed and that modifications in certain 105 features may be made all without departure from the spirit of our invention.

We claim:

1. In a device of the class described, the combination of a portable support, a main 110 shaft, a head carried thereby, a cutting tool and a grinding device carried by the head, means for rotating the head and causing the revolution of the grinding device, and means for rotating the grinding device, substantially as described.

2. In a device of the class described, the combination of a support adapted to be removably located on an engine casting, a vertically reciprocable shaft carried by the support, a head carried by the shaft, a cutting tool adapted for rotation with the shaft, and a grinding device adapted for bodily rotation with the head and for independent rotation, substantially as described.

3. In a unitary portable boring and grinding device, the combination of a support having bearings, a shaft mounted for vertical reciprocation in said bearings, a cutting tool and a grinding device secured to 130

- the lower end of said shaft and rotatable therewith, and means for effecting independent rotation of the grinding device, substantially as described.
5. In a portable boring and grinding device, the combination of a standard adapted to rest upon a cylinder casting, a shaft carried by said standard, a cutting tool secured to the lower end of said shaft, a grinding device also secured to said shaft, and means for effecting planetary movement of said grinding device, substantially as described.
10. In a unitary portable boring and grinding device, the combination of a standard providing bearings, a vertically reciprocable sleeve, a rotatable shaft mounted within the sleeve, a head carried by the shaft, a cutting tool carried by and rotatable with the head, and a grinding wheel also secured to the head, and adapted for simultaneous operation with the cutting tool, and means for effecting planetary movement of the grinding wheel, substantially as described.
15. In a device of the class described, the combination of a casting comprising a base and a standard, the base being adapted to rest upon a cylinder casting, a rotatable shaft carried by the standard, a head secured to the lower end of the shaft, a cutting tool and a grinding device mounted for radial adjustment in the head, and a second shaft arranged internally of the first shaft and adapted to effect with the first shaft a planetary movement of the grinding device, substantially as described.
20. In a device of the class described, the combination of a standard, a shaft mounted for vertical reciprocation on the standard, a head carried by the shaft, said head being provided with radial grooves, a cutting tool and a grinding device mounted in said grooves with capacity for radial adjustment, a second shaft arranged internally of the first shaft and gearing connecting the second shaft to the grinding device, the parts being arranged for independent or simultaneous operation of the cutting and grinding devices, substantially as described.
25. In a device of the class described, the combination of a support adapted to be removably located on an engine casting, a vertically reciprocable shaft carried on the support, a head carried by the shaft, a cutting tool adapted for rotation with the shaft, a grinding device also adapted for rotation with the shaft, means for effecting independent rotation of the grinding device, and means permitting bodily movement of the grinding device toward and from the center of said shaft, substantially as described.
30. In a device of the class described, the combination of a support adapted to be removably located on an engine casting, a vertically reciprocable shaft carried on the support, a head carried by the shaft, means on said head adapted to accommodate a cutting tool, a grinding device mounted on said head, means carried by the head for effecting independent rotation of the grinding device, and means permitting radial adjustment of the grinding device relative to said head, substantially as described.
35. Signed at Ashland, Kentucky, this 13th day of June, 1919.
